UNITED STATES PATENT OFFICE

2,502,722

MUSICAL INSTRUMENT

Elliot Handler, Los Angeles, Calif., assignor to
 Mattel Creations, Los Angeles, Calif., a firm
 composed of Elliot Handler and Louis Green-
 wald

Application November 21, 1947, Serial No. 787,434

5 Claims. (Cl. 84—403)

1

My invention relates to a musical instrument, but more specifically to a new and novel type of construction particularly adaptable for use in connection with miniature or toy pianos.

It is among the objects of my invention to provide a miniature piano which, by reason of its new and novel construction, can be quickly and inexpensively manufactured and assembled, and yet which has a true chromatic scale and a true and undistorted tone.

Miniature pianos are old in the art and well known to the toy and novelty industry. However, due to heretofore known methods of construction, such pianos have not had true tones or were costly to assemble and produce.

It is an object of my invention to produce a harmonic comb of a one-piece construction, but having new and novel features which produce true chromatic tones and which is free from undesirable vibrations.

One-piece musical combs are known to the art. It has, however, been the experience of the art and industry that no satisfactory method has heretofore been devised for mounting such musical combs as an integral unit which was both free from undesirable vibrations and inexpensive to assemble.

It is also among the objects of my invention to produce a new and novel hammer or means for striking the vibrating members in which it is impossible to hold the hammer against the vibrating members, thereby damping the vibrations.

Other and further objects and advantages of my invention will become apparent from the drawings and the specifications relative thereto.

In the drawings:

Figure 1 is a sectional plan view having a portion thereof broken away to show construction details.

Figure 2 is a sectional view taken on line 2—2 of Figure 1.

Figure 3 is a sectional view taken on line 3—3 of Figure 1, showing one of the keys in operating position.

Figure 4 is an enlarged isometric view of a portion of the sound producing comb.

Figure 5 is a top plan view of the sound producing comb.

Figure 6 is an enlarged detail sectional view illustrating the method of mounting the sound producing comb.

The essential features of my invention include a base 10 having a sound producing comb 11 mounted thereon by means of a bridge 12 and

2

a plurality of keys 13 adapted to cause musical vibrations in the comb 11.

Referring to Figure 5, it will be noted that the sound producing comb 11 comprises a mounting strip 16 and a plurality of vibrating members 17 joined to the mounting strip 16 as an integral part thereof by means of a connecting link 18. It will be noted that the entire assembly is formed of a one-piece construction, which is relatively simple and inexpensive to make. The process of stamping from a flat sheet will readily produce the entire musical comb 11.

The vibrating members 17 define spaces 20 having enlarged apertures 21 adjacent the mounting strip 16. The vibrating members 17 are attached to the mounting strip 16 by means of the connecting link 18 which is relatively thinner in cross-section than the vibrating members 17 on the mounting strip 16, thereby defining 20 transverse grooves 21 and 22. These transverse grooves 21 and 22 can easily be formed by a process of milling or coining or any other suitable means.

The important feature of this construction lies 25 in the simplicity of manufacture and the fact that assembly problems are reduced to a minimum in that connecting the mounting strip 16 to the bridge 12 suspends the musical comb in the proper position for free and true vibration.

Another important feature of this construction 30 lies in the fact that the vibrating members 17 are connected with the mounting strip 16 by a reduced section 18, which is highly essential in producing a true tone. This is because such a construction results in a substantially free suspension of the vibrating members 17 so that there 35 is no solid member in contact therewith, which might interfere with the vibrations.

The mounting bridge 12 comprises a pair of 40 upright posts 30 disposed at each end thereof and a bridge member 31 supported by said posts and formed with a longitudinal groove 32. The lower end of the posts 30 are secured to the base 10 by any suitable means, such as screws, welding, or any other suitable means of adhesion. The bridge member 31, together with the base 10, define a longitudinal opening through which 45 keys 13 are disposed, as will be explained later.

In order to obtain a true vibration of the vibrating members 17 free of other undesirable vibrations, it is essential that the musical comb be secured by some means which results in the relatively tight or secure fitting and which prevents any vibration between the mounting strip 16 and the mounting bar 31. This is accomplished in 55

my invention by means of the longitudinal groove 32 and a rod 33 in the following manner. The diameter of the rod 33 and the thickness of the mounting strip 16 are slightly greater than the width of the slot 32 so that when the mounting strip 16 is inserted into the slot 32 and the rod 33 pressed in by means of a hydraulic press or other suitable means, a satisfactorily secure mounting is obtained.

The keys 13 are illustrated in detail in Figures 2 and 3 and comprise a finger section 40, a pivot point 41 and a hammer 42. The hammer section 42 extends inwardly through the longitudinal aperture defined by the cross bar 31 sub-adjacent the vibrating members 17. The hammer section 42 is formed with a vertical bore 43 into which is loosely disposed an anvil 44.

As will be seen in Figure 3, rapid movement downwardly of the finger section 40 of the keys 13 causes the anvil 44 to fly up out of the bore 43, striking the vibrating members 17. The anvil 44 will then drop back into the bore 43 by reason of gravity, but will not interfere with the continued vibrations of the members 17. A sound deadening washer 45 is interposed between the underside of the anvil 44 and the hammer section 42, so that when the anvil drops back into the bore 43, no undesirable noises will be heard.

It will be readily apparent that I have produced a new and novel structure, particularly adaptable to miniature pianos, which greatly reduces the cost of construction and assembly, and yet which results in the production of true tones, free from undesirable vibrations.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. In a musical instrument the combination of: a horizontal bridge formed with an open slot extending longitudinally of said bridge and defined by upper and lower surfaces, a musical comb comprising a plurality of spaced apart chimes extending in a substantially common plane from a straight-edged single mounting strip and all originating along a line parallel to the edge of said mounting strip and formed integral therewith, said chimes being of graduated length to produce tones of graduated pitch, said mounting strip being substantially coextensive in length with the length of said slot in said bridge and located in said slot against one of said surfaces, and a rod having a length substantially the same as the length of the mounting strip tightly wedged in said slot between said mounting strip and the other of said slot surfaces along the entire length of the strip in direct contact therewith whereby the musical comb is rigidly mounted on said bridge.

2. In a musical instrument the combination of: a horizontal bridge formed with an open slot extending longitudinally of said bridge and defined by plane faced and substantially parallel upper and lower surfaces, a musical comb comprising a plurality of spaced apart chimes having rectangular cross sections and extending in a common plane from a straight-edged single mounting strip and all originating along a single line parallel to the edge of said mounting strip and formed inte-

gral therewith, said chimes being of graduated length to produce tones of graduated pitch, said mounting strip being substantially coextensive in length with the length of said slot in said bridge and located in said slot against the upper surface thereof, and a round rod having a length substantially the same as the length of the mounting strip and of a diameter slightly greater than the depth from the bottom of the mounting strip to

10 the lower surface of the slot, said rod being tightly wedged in said slot against the lower surface of said mounting strip along the entire length of the strip in direct contact therewith whereby the musical comb is rigidly mounted on said bridge.

15 3. In a musical instrument, a musical comb comprising a plurality of spaced apart chimes extending in a substantially common plane from a straight-edged single mounting strip and all originating along a line parallel to the edge of said mounting strip, said chimes being of graduated length to produce tones of graduated pitch, each chime being reduced in width at its juncture with the mounting strip, and each chime having a relatively narrow flat bottom cut reducing the depth thereof, the bottom of all of said cuts being 20 parallel to said common plane and located at the point of greatest width reduction and aligned parallel to the edge of the mounting strip, the width reduction and depth cut tending to vibrationally isolate the vibratory body of the chime from the 25 mounting strip, said chimes and said strip being a homogeneous single piece.

30 4. In a musical instrument, a musical comb comprising a plurality of spaced apart chimes having rectangular cross sections of equal dimensions and extending in a common plane from a straight-edged single mounting strip and all originating along a line parallel to the edge of said mounting strip and all having the same thickness 35 as said strip, said chimes being of graduated length to produce tones of graduated pitch, each chime being reduced in width at its juncture with the mounting strip, and each chime having a relatively narrow cut reducing the depth 40 thereof, the bottom of all of said cuts being parallel to said common plane and located at the point of greatest width reduction and aligned parallel to the edge of the mounting strip, the width reduction and depth cut tending to vibrationally isolate the vibratory body of the chime from the 45 mounting strip, said chimes and said strip being a homogeneous single piece.

5. In a musical instrument the combination of: a horizontal bridge formed with an open slot 55 extending longitudinally of said bridge and defined by upper and lower surfaces, a musical comb comprising a plurality of spaced apart chimes extending in a substantially common plane from a straight-edged single mounting strip and all originating along a line parallel to the edge of said mounting strip, said chimes being of graduated length to produce tones of graduated pitch, each chime being reduced in 60 width at its juncture with the mounting strip, and each chime having a relatively narrow flat bottom cut reducing the depth thereof, the bottom of all of said cuts being parallel to said common plane and located at the point of greatest width reduction and aligned parallel to the edge 65 of the mounting strip, the width reduction and depth cut tending to vibrationally isolate the vibratory body of the chime from the mounting strip, said chimes and said strip being a homogeneous single piece, said mounting strip being 70 substantially coextensive in length with the 75

length of said slot in said bridge and located in said slot against one of said surfaces, and a rod having a length substantially the same as the length of the mounting strip tightly wedged in said slot between said mounting strip and the other of said slot surfaces along the entire length of the strip in direct contact therewith whereby the musical comb is rigidly mounted on said bridge.
